(Cl. D29—1)

To all whom it may concern:

Be it known that I, Albert P. Schmid, a citizen of the United States and a resident of Philadelphia, county of Philadelphia, State of Pennsylvania, have invented a new, original, and ornamental Design for a Christmas Tree Ornament, of which the following is a specification, reference being made to the accompanying drawing forming part thereof, and in which:

Fig. 1 is a view in side elevation of a Christmas tree ornament embodying my invention.

Fig. 2 is a section on line 2—2 of Fig. 1.

I claim:

The ornamental design for a Christmas tree ornament, as shown.

ALBERT P. SCHMID.
